DEEP SEA CORING TOWER
Otis Barton, 9% Pacific Tugboat & Salvage Co.,
Pier D, Long Beach, Calif.
Filed Oct. 21, 1963, Ser. No. 317,631
4 Claims. (Cl. 175—6)

This invention relates to a deep sea coring tower for the purpose of obtaining core samples from the floor of a sea or the ocean.

An object of my invention is to provide a novel deep sea coring tower which is entirely self-contained, as far as a bottom platform and bracing is concerned, so that the entire tower with the core barrel and the driving means for the core barrel are contained within a single unit which can be transported as a whole from one position to another in the sea or ocean, and which can be easily and quickly lowered or raised by means of appropriate lifting apparatus, which may be mounted on a barge or vessel.

Another object of my invention is to provide a novel deep sea coring tower of the character stated, in which the driving mechanism for the core barrel is completely contained within the tower, and can be controlled by an electrical cable or conduit which runs to the surface and is there manually manipulated by the operator.

Another object of my invention is to provide a novel deep sea coring tower which will retain its position at the bottom of the sea or ocean, and will not be materially influenced or moved by tides or currents in the sea or ocean.

Another object of my invention is to provide a novel deep sea coring tower of the character stated, which will have sufficient weight and lateral stability to maintain the tower in the position in which it is set at the bottom of the sea or ocean, and which will not tilt, drift, or otherwise alter the position in which it is set until it is desired to move the same, which is accomplished by means of suitable lifting apparatus.

Other objects, advantages and features of my invention may appear from the accompanying drawing, the submitted detailed description and the appended claims.

In the drawing:

FIGURE 1 is a fragmentary perspective view of my deep sea coring tower.

FIGURE 2 is a fragmentary perspective view of the core barrel driving mechanism.

FIGURE 3 is a fragmentary perspective view of the hyperbolic driving hubs.

FIGURE 4 is a fragmentary side view of the core barrel driving mechanism as viewed from line 4—4 of FIGURE 2.

FIGURE 5 is a fragmentary sectional view taken on line 5—5 of FIGURE 4.

FIGURE 6 is a fragmentary vertical sectional view of the driving frame attachment to the floor of the tower as viewed from line 6—6 in FIGURE 1.

FIGURE 7 is a top plan view of the coring tower.

Referring more particularly to the drawing, my vertical coring tower 1 consists of a plurality of vertically extending corner posts 2. These posts are suitably spaced to form a substantially rectangular structure which is braced by means of transverse members 3. The members 3 and the corner posts 2 are fixedly secured together by suitable means, such as welding, brazing, bolting, or the like. The corner posts 2, as well as the braces 3, are preferably made of tubing to minimize the force against the tower created by ocean or sea currents or swells. The entire tower 1 is substantial in height (100 feet more or less) and, consequently, has considerable weight. The base of the tower consists of a plurality of heavy wood

2

or metal timbers or floor beams 4, and intersecting beams 5, which in themselves are very heavy and are of substantial length to thus provide lateral stability to the tower 1. A plurality of angular braces 6 extend from the floor or foundation members 4 to the vertical tower members or corner posts 2, thus bracing the tower against possible lateral movement. The tower 1 is of open construction so that currents and tide movements can flow back and forth through it, and these structures are still sufficiently heavy so that they will not be buoyant to a substantial degree, but will sink rapidly into the ocean or sea until bottom is reached, upon which the floor or base members 4, 5 can rest. The upper end of the tower 1 is square, as shown in FIGURE 7, and a pair of parallel rods 7, 8 are fixedly mounted and are connected by a plate 9, which is formed with a hole or hook structure 10 to be engaged by the lifting apparatus whereby the tower is transported from place to place. With this arrangement the tower, when lifted, places the corner legs 2 and the braces 3 in tension, and also tensions the braces 6 to lift the floor members 4, 5 thus providing adequate structural strength so that the entire tower may be lifted from its upper end without structurally endangering any of the parts.

A base plate 11 is fixedly attached to the floor members 4, 5 of the tower, and this base plate has an opening therethrough through which the core barrel 12 extends to penetrate the ocean floor below the base of the tower. The core barrel 12 extends vertically in the tower 1 for substantially the entire length thereof, and can be lowered 30 and rotated into the ocean floor for the purpose of obtaining a sample or core of that ocean floor. The driving mechanism of the core barrel 12 consists of the following: A pair of hyperbolic driving hubs 13, 14 are each mounted on an inclined shaft 15 and 16. These shafts are mounted 35 at an acute vertical angle to the center line of the core barrel 12 and are driven in a manner to be subsequently described. So that the shafts 15 and 16 may be adequately rotated and without any power connection to the surface, I provide self-contained and immersible driving 40 units for each of these shafts. Each driving unit consists of a sealed box 17, preferably formed of metal, and which is completely filled with a suitable oil or the like surrounding an electric motor 18. These boxes, being completely filled with oil or other fluid, will exclude water and will 45 permit the motor 18 to function properly. The motor shaft 19 projects from the box or housing 17 and is suitably sealed or packed off to prevent intrusion of water. Suitable meshing gears 20 will drive the shaft 16 from the motor shaft 19, thus causing the hubs 13, 14 to rotate 50 and drive the core barrel 12. The two boxes or housings 17 are each set at substantially the same angle as the shafts 15, 16, and the housing is mounted on a base member 21 which is fixedly attached to the base plate 11. The boxes or housings 17 are, in turn, fixedly attached to 55 the base members 21, thus forming an integral unit. Frame members 22 extend upwardly from the housings 17, thus forming additional structural members to support the driving elements of the tower.

A supporting frame 23, formed of structural members, 60 surrounds the bore barrel 12 and is substantially smaller in shape than the tower 1 and extends upwardly in that tower a short distance above the frames 22 of the boxes 17. The frames 22, in turn, are fixedly attached to the frame 23 at one end to again assist in rigidly mounting the housings 65 or boxes 17, and to keep the shafts 15, 16 in proper alignment. The vertical members 24 of the frame 23 are bolted to the base 11 by means of bolts 25 which extend through the base and onto which suitable nuts are threaded, thus fixedly mounting the frame 23 to the base 70 11 and uniting this assembly with the tower 1 and its base members 4, 5, so that a single unitary structure is provided. Hermetically sealed battery boxes 26 are pro-

engaging the outer surface of the core barrel to rotate said barrel and feed the barrel downwardly into the formation,
 a base frame fixedly mounted on the base plate,
 said box being fixedly mounted on the base frame at an 5
 acute angle to the center line of the core barrel,
 a supporting frame surrounding the lower end of the
 core barrel within the tower,
 means fixedly attaching the bottom end of the supporting frame to the base plate, 10
 means fixedly attaching the base frame to the supporting frame at an acute angle to the horizontal,
 an electric storage battery mounted in the tower, and
 electrically connected to said motor,

another hermetically sealed box on said base plate, said storage battery being mounted therein.
